UNITED STATES PATENT OFFICE

JACOB TELLER, OF NEW ROCHELLE, AND ARTHUR P. SCHULZ, OF NEW YORK, N. Y., ASSIGNEES TO TELLER CORPORATION, OF CHATTANOOGA, TENNESSEE, A CORPORATION OF TENNESSEE

DESIGN FOR A COMBINED GAS OR ELECTRIC CABINET RANGE AND REFRIGERATOR

Application filed October 10, 1931. Serial No. 41,362. Term of patent 14 years.

To all whom it may concern:

Be it known that we, JACOB TELLER and ARTHUR P. SCHULZ, citizens of the United States, and residents of New Rochelle, in the county of Westchester, N. Y., and New York city, in the county of New York, N. Y., respectively, have invented a new, original, and ornamental Design for a Combined Gas or Electric Cabinet Range and Refrigerator, of which the following is a specification, ref-

erence being had to the accompanying drawings, forming a part thereof.

Figure 1 is a perspective view of the range and refrigerator. Figure 2 is a similar view with the several doors open.

We claim the ornamental design for a combined gas or electric cabinet range and refrigerator, as shown.

JACOB TELLER.
ARTHUR P. SCHULZ.
